ATTORNEY

UNITED STATES PATENT OFFICE.

ELMER B. STONE, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

Application filed April 17, 1923. Serial No. 632,615.

My invention relates more especially to that class of locks known as shackle locks, and an object of my invention, among others, is to provide a lock of this class that shall be extremely strong to withstand forces that may be applied to disrupture it.

One form of lock embodying my invention and in the construction and use of which the objects herein set out, as well as others, 10 may be attained, is illustrated in the accompanying drawings, in which—

Figure 1 is a front view of my improved lock.

Figure 2 is an edge view of the same.

Figure 3 is an end view with the shackle broken off.

Figure 4 is a view similar to Fig. 3, but showing one manner of use of the lock to embody my invention.

20 In the use of locks of this type, it frequently occurs that, owing to certain shapes of the engaged parts, one branch of the shackle will be so insecurely held as to permit it to be pried loose with comparatively 25 little force, this defect taking place close to the lock case.

In order to overcome this objection I have provided means for reinforcing the shackle at this point, such means being shown in 30 the accompanying drawings, in which the numeral 5 indicates a lock case having an inclined projection 6 in which a key cylinder 7 is located. Openings are formed through the case preferably from one end to the other 35 and a two-armed shackle 8 extends through these openings, the shackle being notched along its length as at 9 to receive locking bolts operated by the mechanism within the case including the projection 6.

40 A lug 10 extends from one end of the case 5, this lug being preferably integrally formed with the case and containing a portion of the opening for an arm of the shackle 8. This lug at one edge constitutes a hub 45 that is preferably substantially round in cross section to conform to the shape of the arm of the shackle 8, and from this point toward the center of the lock case the lug is made with a nose 11, it, however, being maintained of sufficient thickness to resist forces 50 that may be applied to the shackle to disrupt the parts. I prefer to locate this lug appurtenant to one of the shackle arms only, as in most cases this will be found sufficient, but 55 it will be understood that in cases where cir-

cumstances may require the lug may be extended from the case appurtenant to both of the shackle arms.

In one instance of use of this lock, a lock plate 12 is employed, as shown in Fig. 4, this plate having a hole 13 and a notch 14 in one end, the plate being employed to secure a locked member and the lock being employed to secure the plate. Said hole and notch are, however, so close together as to make it impracticable to locate the arms of the shackle so close together, owing to a weakness in the lock structure that would result from such a construction. Therefore, in order to avoid this difficulty, the nose 11 is 60 provided to engage within the notch 14 appurtenant to one shackle arm, the other shackle arm passing through the hole 13. This construction provides means whereby the working mechanism of the lock need not 65 be weakened, and at the same time the locked member will be held in a strong and efficient manner.

I claim—

1. A lock case having a lug extending outwardly from one end thereof, said lug comprising a hub and an elongation extending from said hub along the end of the case toward the opposite edge thereof, said lug also having an opening extending into the case 85 through said hub to receive one arm of a shackle, the end of said elongation being spaced from the other shackle arm for locked engagement with a member located between the end of said elongation and the other 90 shackle arm, there being another shackle receiving opening in the case, and a shackle extending into said openings to be held by mechanism within the case.

2. A lock comprising a case having a lug 95 located on one end thereof, said lug comprising a hub and an elongation extending from said hub along the end of the case toward the center and opposite edge thereof, said lug having an opening into said case 100 and through said hub to receive one arm of a shackle, the end of said elongation being spaced from the other shackle arm for locked engagement with a member located between the end of the elongation and said other 105 shackle arm, a projection extending at an angle from the body of the case at the opposite end thereof from said lug, and a shackle projecting through said openings into the case and on opposite sides of said angular 110

projection, said shackle being held by mechanism located within said case.

3. A lock case having a lug extending outwardly from one end thereof, said lug comprising a hub and an elongation extending from said hub along the end of the case toward the opposite edge thereof to locate the holding means of the lock nearer together than are the shackle arms, said lug also having an opening extending into the case

through said hub to receive one arm of a shackle, the end of said lug being positioned for locked engagement with a member located between the end of the elongation and said other shackle arm, there being another shackle receiving opening in the case, and a shackle extending into said opening to be held by mechanism within the case. 15
